US00D943614S

(12) **United States Design Patent** (10) **Patent No.:** **US D943,614 S**
Meng et al. (45) **Date of Patent:** **** Feb. 15, 2022**

(54) **DISPLAY SCREEN OR PORTION THEREOF WITH AN ANIMATED GRAPHICAL USER INTERFACE**

(71) Applicant: **Lenovo (Beijing) Co., Ltd.**, Beijing (CN)

(72) Inventors: **Fanxiao Meng**, Beijing (CN); **Wei Zhang**, Beijing (CN); **Lei Zhang**, Beijing (CN)

(73) Assignee: **Lenovo (Beijing) Co., Ltd.**, Beijing (CN)

(**) Term: **15 Years**

(21) Appl. No.: **35/509,900**

(22) Filed: **Oct. 22, 2019**

(80) **Hague Agreement Data**

Int. Filing Date: **Oct. 22, 2019**

Int. Reg. No.: **DM/209288**

Int. Reg. Date: **Oct. 22, 2019**

Int. Reg. Pub. Date: **Jul. 24, 2020**

(57) **CLAIM**

The ornamental design for a display screen or portion thereof with an animated graphical user interface, as shown and described.

DESCRIPTION

2.1: First image

2.2: Second image

2.3: Third image

4.1: First image

4.3: Second image

4.5: Third image

The process or period in which one image transitions to another image forms no part of the claimed design.

The broken line showing of the phone and the display screen or a portion thereof is for the purpose of illustrating environment and forms no part of the claimed design.

(Continued)

The broken line showing of elements on the display screen illustrate portions of the graphical user interface and form no part of the claimed design.

1 Claim, 6 Drawing Sheets
